[57] CLAIM

The ornamental design for a vehicular telephone set of
similar article, shown and described.

DESCRIPTION

FIG. 1 is a front elevation of a vehicular telephone set
or similar article showing our new design;

FIG. 2 is a rear elevation thereof;

FIG. 3 is a left side elevation thereof;

FIG. 4 is a right side elevational thereof;

FIG. 5 is a top plan view thereof;

FIG. 6 is a bottom plan view thereof;

FIG. 7 is a top perspective view thereof;

FIG. 8 is a top perspective view thereof, with the hand-
set removed from the telephone base; and

FIG. 9 is a top perspective view of the telephone set
mounted on a vehicle console.

The broken lines are shown for illustrative purposes
only.
